UNITED STATES PATENT OFFICE

2,416,960

BRAKE

Edward J. Simanek, Chicago, Ill., assignor to
American Steel Foundries, Chicago, Ill., a corporation of New Jersey

Application January 22, 1944, Serial No. 519,286

24 Claims. (Cl. 188—56)

1

My invention relates to brakes and more particularly to a novel brake arrangement for a railway car truck.

The general object of my invention is to design a novel clasp brake rigging in which brake drums, as well as the truck wheels, are engaged by clasp brake means.

A specific object of my invention is to design a brake rigging such as above described in which a pair of beams are suspended at opposite sides of each wheel, said beams carrying friction means for engagement with said wheel and with a brake drum rotatable therewith and adjacent thereto. The beams are operatively connected to interconnected live and dead truck levers.

In one embodiment of my invention the beams are provided with trunnion ends for pivotal connection to brake hangers and to the associated brake heads, and in another illustrated embodiment of my invention, the ends of the beams are received within slots through the brake heads and are pivoted thereto on substantially vertical axes to afford equalization of wear of the contacting surfaces of the brake shoes and the wheel and drum respectively, the heads being pivoted to hangers which are mounted on the truck frame.

In the drawings,

Figure 1 is a fragmentary top plan view of a railway car truck embodying my invention, only one-half of the truck being illustrated inasmuch as it is symmetrical about its longitudinally center line.

Figure 2 is a side elevation of the structure shown in Figure 1.

Figure 3 is a sectional view taken in the planes indicated by the line 3—3 of Figure 1.

Figure 4 is an end view taken from the left as seen in Figures 1 and 2.

Figures 5 and 6 illustrate a modification of my invention, Figure 5 being a fragmentary top plan view of the truck, and Figure 6 being a fragmentary side elevation.

In each of said figures certain details may be omitted where more clearly seen in other views.

Describing my invention in detail and referring first to the embodiment thereof illustrated in Figures 1 to 4 inclusive, the truck frame generally designated 2 comprises a side rail 4 at each side thereof merging with the end rails 6, 6 and the spaced intermediate transoms 8, 8, said transoms being formed and arranged in conventional manner for the suspension of a truck bolster (not shown) disposed therebetween. The side rail is formed adjacent each end thereof with the spaced

2

depending pedestal legs or jaws 10, 10 adapted for the reception therebetween of journal boxes (not shown) associated in the usual manner with the wheel and axle assemblies 12, 12, each assembly including a brake disc 14 mounted adjacent each wheel for rotation therewith. It will be understood by those skilled in the art that the journal boxes at each side of the truck afford support in the conventional manner for an equalizer 15 (Figure 3) carrying resilient means diagrammatically indicated at 17, said resilient means affording support in the usual manner for the side rail 4 of the truck frame.

Intermediate the wheel and axle assemblies 12, 12 are the brake beams 16, 16 having trunnion ends pivoted to the inboard and outboard hangers 20 and 22 connected respectively at 24 and 26 to brackets 28 and 30, the bracket 28 being formed on the adjacent transom 8, and the bracket 30 being formed on the gusset 32 at the juncture of the transom 8 with the side rail 4. Each beam 16 is pivoted intermediate its ends at 34, as best seen in the left half of Figure 1, to a jaw 36 pivotally connected at 38 to the lower end of the adjacent live truck lever 40, said jaw also being pivotally connected at 42 to a balance hanger 44 pivoted to a balance hanger bracket 48 mounted at 50 on the adjacent gusset 32.

Outboardly of the wheel and axle assemblies 12, 12 are the brake beams 52, 52 substantially identical in form with the beams 16, 16 and comprising trunnion ends pivotally mounted on the inboard and outboard hangers 54 and 56, said hangers being pivoted respectively at 58 and 60 to brackets 62 and 64, the inboard bracket 62 being formed on the end rail 6, and the outboard bracket 64 being formed on the side rail 4 adjacent its juncture with the end rail 6. A jaw 66 is pivotally connected at 68 to each beam 52 intermediate its ends, said jaw being pivotally connected at 70 to the lower end of the adjacent dead truck lever 72, the upper end of said dead truck lever being pivotally connected at 74 to the bracket 76 mounted as at 78, 78 on the side rail 4.

The trunnion ends of the beams 16, 16 and 52, 52 support brake heads 80, 80 carrying friction shoes 82, 82 for engagement respectively with the drums 14, 14 and the wheels of the wheel and axle assemblies 12, 12. The arrangement of the brake heads 80, 80 and their connection to the beams is illustrated at the left end of Figure 2 and in the end view of Figure 4.

The live and dead truck levers 40 and 72 associated with each wheel of the wheel and axle assemblies 12, 12 are connected by a pull rod 84

which is pivoted at one end thereof as at 86 to the dead truck lever 72 and pivoted at the opposite end thereof as at 88 to the live truck lever 40.

A power cylinder device 90 is secured as at 92, 92 to the side rail 4, and the piston rod 94 of said device is pivotally connected at 96 to the outboard end of the live cylinder lever 98, said cylinder lever being pivotally and adjustably connected at 100 to the pull rod 102, the opposite end of which is pivotally and adjustably connected at 104 to the dead cylinder lever 106, the outboard end of which is pivotally connected at 108 to the slack adjuster device 110 secured as at 112, 112 to the power cylinder device 90. The inboard end of each cylinder lever is pivotally connected at 114 to a pull rod or link 116, the opposite end of which is pivotally connected at 118 to the upper end of the adjacent live truck lever 40, and each cylinder lever is afforded slidable support adjacent its inboard end by means of the support bracket 120 secured as at 122 to the adjacent gusset 32. The live cylinder lever 98 is afforded additional support adjacent its outboard end by means of the bracket 124 secured as at 126, 126 to the outboard edge of the side rail 4.

During actuation of my novel brake rigging, the piston rod 94 moves to the left as seen in Figure 1, causing the live cylinder lever 98 to rotate in a clockwise direction about the pivot point 100, thus causing the associated pull rod or link 116 to move to the right, as seen in Figure 2, whereby the associated live truck lever 40 is rotated in a clockwise direction about its pivot point 88, the pull rod 84 causing the dead truck lever 72 at the left of Figure 2 to rotate in a counterclockwise direction about its pivot point 74. At the same time, the pull rod 102 moves to the left as seen in Figure 1, thus actuating the brake rigging at the right end of the truck through the dead cylinder lever 106 in substantially the reverse of the manner described for the rigging at the left end of the truck. It will be understood that the pivotal connection of the beams 16, 16 to the jaws 36, 36 affords equalized pressure by the brake shoes 82, 82 against the drums 14, 14 and the wheels of the wheel and axle assemblies 12, 12.

A modification of my invention is illustrated in Figures 5 and 6 wherein the truck frame generally designated 152 is supported at each end thereof from a wheel and axle assembly 154 as in the previously described embodiment, the wheel and axle assembly 154 comprising a brake drum 156 adjacent each wheel. It will be understood that the arrangement shown in Figures 5 and 6 is identical with that illustrated in Figures 1 to 4 except for the fact that each brake beam 158 is received at each end thereof within a slot 160 in the associated brake head 162 and pivoted thereto as at 164 on a substantially vertical axis, the brake heads 162, 162 carrying brake shoes 166, 166 for engagement respectively with the drum 156 and the wheel 168 of the wheel and axle assembly 154. The outboard brake head 162 is pivotally connected at 170 to a hanger 172, the upper end of which is pivotally connected at 174 to a bracket 176 formed on the truck frame 152, and the inboard brake head is pivotally connected at 178 to a hanger 180, the upper end of which is pivotally connected at 182 to the bracket 184 formed on the end rail 186 of the truck frame 152.

A jaw 188 is pivotally connected at 190 to the brake beam 158 intermediate its ends, said jaw being pivotally connected at 192 to the lower

end of the dead truck lever 194, the upper end of which is pivotally fulcrumed at 196 to the bracket 198 secured to the truck frame as in the previously described embodiment. Intermediate its ends the dead truck lever is pivotally connected at 200 to a pull rod 202, the opposite end of which is connected to the associated live truck lever as in the arrangement illustrated in Figures 1 to 4.

It will be understood that the left end only of the truck is illustrated in Figures 5 and 6, inasmuch as the only difference between this arrangement and that previously described is the manner in which the brake heads are connected to the beam 158 and to the hangers 172 and 180.

It will also be understood that the connection between the brake beam 158 and the shoes 162, 162, as illustrated in Figures 5 and 6, facilitates equalization of wear of the contacting surfaces of the shoes 166, 166 against the drum 156 and the wheel 168 respectively.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a brake arrangement for a railway car truck comprising a truck frame and spaced supporting wheel and axle assemblies each including an axle, spaced wheels mounted thereon and brake drums adjacent respective wheels, brake rigging comprising brake beams at each side of the truck, said beams being disposed at opposite sides of the associated wheels, friction means carried by each beam for engagement with the adjacent wheel and the associated disc, live truck levers connected to the beams inwardly of said assemblies, dead truck levers connected to the beams outwardly of said assemblies, pull rods connecting the adjacent live and dead truck levers, and operating means associated with the live truck levers, said operating means comprising a power cylinder device mounted on said frame, interconnected live and dead cylinder levers connected to opposite ends of said device, and an operative connection between each cylinder lever and the adjacent live truck lever.

2. In a brake arrangement for a railway car truck, a truck frame, spaced supporting wheel and axle assemblies each comprising an axle with a wheel mounted thereon adjacent each end thereof and a brake disc adjacent each wheel, brake rigging for each side of the truck comprising brake beams at opposite sides of each assembly, brake shoes carried by the outboard ends of said beams for engagement with said wheel, other brake shoes carried by the inboard ends of said beams for engagement with the associated disc, jaws pivotally connected to respective beams approximately midway intermediate the ends thereof, interconnected live and dead truck levers pivotally connected to respective jaws, and operating means for said live truck levers, said operating means comprising a power cylinder device mounted on the side of said frame, interconnected live and dead cylinder levers connected to opposite ends of said device, and an operative connection between each cylinder lever and the adjacent live truck lever.

3. In a brake arrangement for a railway car truck, a truck frame, a supporting wheel and axle assembly comprising an axle, a wheel thereon, and a brake drum adjacent said wheel, inter-

connected live and dead truck levers disposed intermediate said drum and said wheel, a brake beam operatively connected substantially midway between its ends to each of said levers, brake shoes carried by the inboard ends of said beams and formed and arranged for braking engagement with said drum, brake shoes carried by the outboard ends of said beams and formed and arranged for braking engagement with said wheel, and operating means connected to the live truck lever, said operating means comprising a power cylinder device mounted on said frame, a cylinder lever connected at its outboard end to said device and at its inboard end to said live truck lever, and a fulcrum for said cylinder lever intermediate its ends.

4. In a brake arrangement for a railway car truck, a truck frame, spaced supporting wheel and axle assemblies each comprising an axle with a wheel mounted thereon and a brake disc adjacent said wheel, brake beams at opposite sides of each wheel, friction means carried by corresponding ends of said beams for engagement with said wheel, other friction means carried by opposite corresponding ends of said beams for engagement with the associated disc, jaws pivotally connected to respective beams approximately midway intermediate the ends thereof, interconnected live and dead truck levers connected to respective jaws, and operating means for said live truck levers, said operating means comprising a power cylinder device mounted on said frame, interconnected live and dead cylinder levers operatively connected to opposite ends of said device, and an operative connection between each cylinder lever and the adjacent live truck lever.

5. In a brake arrangement for a railway car truck, a truck frame, spaced supporting wheel and axle assemblies each comprising an axle with spaced wheels mounted thereon and a brake disc adjacent each wheel, brake beams at opposite sides of each wheel, brake shoes carried by corresponding ends of said beams for engagement with said wheel, other brake shoes carried by the opposite corresponding ends of said beams for engagement with the associated disc, interconnected live and dead truck levers connected to respective beams intermediate their ends, a power cylinder device on each side of said frame, interconnected live and dead cylinder levers connected to opposite ends of said device, and an operative connection between each cylinder lever and the adjacent live truck lever.

6. In a brake arrangement for a railway car truck comprising a truck frame and spaced supporting wheel and axle assemblies each including an axle, spaced wheels mounted thereon and brake drums adjacent respective wheels, brake rigging comprising brake beams at each side of the truck, said beams being disposed at opposite sides of the associated wheels, friction means carried by each beam for engagement with the adjacent wheel and the associated disc, live truck levers connected to the beams inwardly of said assemblies, dead truck levers connected to the beams outwardly of said assemblies, pull rods connecting the adjacent live and dead truck levers, and operating means associated with the live truck levers.

7. In a brake arrangement for a railway car truck comprising a truck frame and spaced supporting wheel and axle assemblies each including an axle, spaced wheels thereon, and brake drums adjacent said wheels, brake rigging comprising

brake beams at opposite sides of each wheel, means suspending said beams at opposite ends thereof from said frame, brake shoes carried by each beam at opposite ends thereof for braking engagement with the wheel and the adjacent drum respectively, and actuating means for said beams, said actuating means comprising jaws pivoted to said beams approximately midway intermediate their ends, interconnected live and dead truck levers pivotally connected to the jaws on respective beams, and operating means for said live truck lever.

8. In a brake arrangement, a vehicle frame, a supporting wheel and axle assembly comprising a wheel and an adjacent brake drum, brake beams at opposite sides of said assembly, each of said beams carrying at opposite ends thereof friction means for engagement with said wheel and said drum respectively, interconnected live and dead levers operatively connected to respective beams, and operating means for said live levers, said operating means comprising a power cylinder device on said frame, a cylinder lever connected at its outboard end to said device and at its inboard end to said live truck lever, and a fulcrum for said cylinder lever intermediate its ends.

9. In a brake arrangement for a railway car truck, a truck frame, a supporting wheel and axle assembly comprising an axle, spaced wheels thereon and a brake drum adjacent each wheel, and brake rigging comprising live and dead truck levers at opposite sides of said assembly adjacent each wheel, clasp brake means for said wheel and the adjacent drum, an operative connection between said clasp brake means and said levers, and operating means comprising a power cylinder device on said frame, a cylinder lever connected at its outboard end to said device and at its inboard end to said live truck lever, and a fulcrum for said cylinder lever intermediate its ends.

10. In a brake arrangement for a railway car truck, a truck frame, a supporting wheel and axle assembly comprising an axle, spaced wheels thereon and a brake drum adjacent each wheel, and brake rigging comprising live and dead truck levers at opposite sides of said assembly adjacent each wheel, clasp brake means for said wheel and the adjacent drum, an operative connection between said clasp brake means and said levers, and operating means for said live lever, said clasp brake means comprising brake beams hung from the frame and carrying shoes at their opposite ends for cooperation with the peripheries of said wheel and said drum respectively.

11. In a brake arrangement for a railway car truck, a truck frame, a supporting wheel and axle assembly comprising an axle, a wheel thereon, and a brake drum adjacent said wheel, interconnected live and dead truck levers disposed intermediate said drum and said wheel, a brake beam operatively connected substantially midway between its ends to each of said levers, brake shoes carried by the inboard ends of said beams and formed and arranged for braking engagement with said drum, brake shoes carried by the outboard ends of said beams and formed and arranged for braking engagement with said wheel, and operating means connected to the live truck lever.

12. In a brake arrangement for a railway car truck, a truck frame, spaced supporting wheel and axle assemblies each comprising an axle with wheels mounted thereon and a brake disc adjacent each wheel, a pair of spaced independent

brake beams at each side of each assembly, friction means directly mounted on corresponding ends of said beams for engagement with said wheels, other friction means directly mounted on opposite corresponding ends of said beams for engagement with the associated discs, jaws pivotally connected to respective beams approximately midway intermediate the ends thereof, interconnected live and dead truck levers connected to respective jaws, and operating means for said live truck levers.

13. In a brake arrangement for a railway car truck, a truck frame, spaced supporting wheel and axle assemblies each comprising an axle with spaced wheels mounted thereon, and a brake disc adjacent each wheel, brake beams at opposite sides of each wheel, brake shoes carried by the outboard ends of said beams for engagement with said wheel, other brake shoes carried by the inboard ends of said beams for engagement with the associated disc, jaws pivotally connected to respective beams approximately midway intermediate the ends thereof, interconnected live and dead truck levers connected to respective jaws, and operating means for said live truck levers.

14. In a brake arrangement for a railway car truck, a truck frame, a supporting wheel and axle assembly comprising an axle, spaced wheels thereon and a brake drum adjacent each wheel, and brake rigging comprising live and dead truck levers at opposite sides of said assembly adjacent each wheel, clasp brake means for said wheel and the adjacent drum, an operative connection between said clasp brake means and said levers, and operating means for said live levers.

15. In a brake arrangement for a wheel and axle assembly comprising a wheel and a brake drum adjacent thereto, interconnected live and dead truck levers at opposite sides of said assembly, said levers being disposed intermediate said drum and said wheel, a brake beam at each side of said assembly and operatively connected intermediate its ends to the associated lever, brake shoes carried by each beam at opposite ends thereof for cooperation respectively with said wheel and said drum, and operating means for said live lever.

16. In a brake arrangement, a vehicle frame, a supporting wheel and axle assembly comprising wheels and adjacent brake drums, spaced independent brake beams at each side of said assembly, each of said beams having directly mounted thereon at opposite ends thereof friction means for engagement with a wheel and the adjacent drum respectively, interconnected live and dead levers operatively connected to respective beams, and operating means for said live levers.

17. In a brake arrangement for a railway car truck, a truck frame, a supporting wheel and axle assembly comprising a wheel and a brake drum spaced therefrom, substantially vertical interconnected live and dead truck levers at opposite sides of said assembly, and clasp brake means for said drum and said wheel, said clasp brake means being operatively associated with said levers, said levers being disposed in a vertical plane passing between said wheel and drum.

18. A duplex clasp brake arrangement for a wheel and axle assembly having a brake drum

5 adjacent each wheel comprising interconnected live and dead substantially vertical levers at opposite sides of said assembly adjacent each wheel, and wheel and drum engaging shoes operatively connected to each lever, said levers being disposed inboard the wheel and outboard the drum.

19. In a brake arrangement, a vehicle frame, a supporting wheel and axle assembly comprising a wheel and an adjacent brake drum, brake beams at opposite sides of said wheel and drum, inboard and outboard ends on each beam, friction shoes directly and pivotally connected to each of said ends for engagement with said wheel and drum respectively, and interconnected live and dead levers operatively connected to respective beams intermediate the inboard and outboard ends thereof.

20. In a brake arrangement, a vehicle frame, a supporting wheel and axle assembly comprising a wheel and an adjacent brake drum, brake beams at opposite sides of said wheel and drum, inboard and outboard ends on each beam, friction means carried by each of said ends for engagement with said wheel and drum respectively, and interconnected live and dead levers operatively connected to respective beams, said levers being disposed inboard the wheel and outboard the drum.

21. In a brake arrangement, a vehicle frame, a supporting wheel and axle assembly comprising a wheel and an adjacent brake drum, brake beams at opposite sides of said wheel and drum, inboard and outboard ends on each beam, friction means carried by each of said ends for engagement with said wheel and drum respectively, and means operatively connected to each beam between the friction means carried thereby.

22. In a brake arrangement, a vehicle frame, a supporting wheel and axle comprising a wheel and an adjacent brake drum, clasp brake means for said wheel and drum, and means operatively connected to said clasp brake means and disposed in a plane passing between said wheel and drum.

23. In a brake arrangement, a vehicle frame, a supporting wheel and axle assembly comprising a wheel and an adjacent brake drum, clasp brake means for said wheel and drum, and means operatively connected to said clasp brake means and disposed inboard the wheel and outboard the drum.

24. A duplex clasp brake arrangement for a wheel and axle assembly having a wheel and an adjacent brake drum comprising clasp brake means for said wheel and drum, and means operatively interconnecting said clasp brake means and disposed in a plane passing between said wheel and drum.

EDWARD J. SIMANEK.
